UNITED STATES PATENT OFFICE.

CHARLES W. COLLINS, OF GREENWICH, NEW YORK.

SWITCH.

Application filed February 16, 1926. Serial No. 88,637.

This invention relates to switches and more particularly to tongue switches, and has for its object the provision of a novel means for holding down the point of the 5 switch tongue.

Another object is to provide holding down mechanism which will be applicable to standard trailing point switches where the 10 standard spring or lock mechanism is not required, and yet it is desirable to hold the tongue point to the bed of the switch to prevent excessive wear and keep the tongue in the worn switch bed from excessive noise due to it jumping about, and in extreme cases 15 from jumping out of place due to the force of traffic passing over it.

A further object is to provide a switch having the novel design, construction and combination of parts hereinafter described 20 in the following specification and illustrated in the accompanying drawings:

In the drawings:—

Figure 1 is a plan view of a portion of a standard tongue switch having my invention 25 applied thereto.

Figure 2 is a sectional elevation on the line II—II of Figure 1.

Figure 3 is a view similar to Figure 1 showing a modified embodiment of my invention. 30

Figure 4 is a sectional elevation on the line IV—IV of Figure 3.

Referring more particularly to the drawings the numeral 2 designates the switch 35 body, which is provided with a longitudinal groove or recess 3 forming a tongue bed, to receive the switch tongue 4.

The switch tongue 4 is provided with a 40 downwardly extending lug 5 at a point intermediate its ends, which lug is apertured at 6 in a direction transversely of the longitudinal axis of the tongue.

A standard spring box 7, such as is ordinarily used to house the spring operating 45 mechanism of a trailing switch, is secured by bolts 8 to the switch body 2 and the switch body 2 and box 7 are apertured to form a passage 9.

A casting 10 having spaced vertically extending ears 11 is secured in the box 7 by the 50 bolts 8. A crank lever 12 is pivotally mounted between the ears 11 by a pivot pin 14. The forward arm 15 of the crank lever is slotted longitudinally at 16 to receive a holding down bar or rod 17. The other or 55 rear arm 18 of the crank lever is apertured

at 19 to receive the downwardly bent rear end 20 of the bar or rod 17. The rear arm 18 of the crank lever is provided adjacent its rear end with a threaded aperture 21 in 60 which is threaded an adjusting screw 22 adapted to be threaded through said aperture and bear against the casting 10 to rock the crank lever about the pivot pin 14.

The rod or bar 17 has its forward end 65 mounted in the aperture 6 of the lug 5 and said lug is adapted to move along said rod as the switch tongue is moved from side to side of the groove or bed 3 of the switch body 2. 70

A stiffener tube 24 is mounted on the rod 17 to stiffen and strengthen it against bending strains.

In operation, after the parts are assembled 75 the screw 22 is threaded through the aperture 21 in the arm 18 of the crank lever thus forcing the arm 15 of the crank lever downwardly against the rod 17 and in turn forcing the rod 17 downwardly against the lug 5 so as to hold the tongue 4 in its bed 3. 80

If it is desired to remove the rod 17 for any reason it is only necessary to remove the 85 screw 22 and withdraw the rod into the box 7 and then tilt it upwardly until it clears the box and then remove it, the passage 9 being of sufficient size to permit this tilting of the rod 17.

In the modified construction of Figures 3 and 4 a telescoping holding down rod or bar 17^a is provided for holding down the 90 tongue. The rod 17^a is composed of a solid bar portion 25 adapted to be slidably fitted within the aperture 6 in the lug 5, a tubular portion 26 welded to the bar portion 25 and extending through the passage 9, and a 95 second bar portion 27 telescoped within the tubular portion 26 and removably held in position by a pin 28 which extends downwardly through the tubular portion 26, the bar 27 and flange 29 of a casting 10^a which 100 is substituted for the casting 10 of the preferred embodiment of my invention.

The rear end of the bar portion 27 is enlarged to form a head 30 which is apertured 105 to receive a bolt 31, which bolt extends downwardly into a squared recess 32 in the casting 10^a and is threaded in a nut 33 mounted in said recess. The nut 33 is slidably mounted in the recess 32 and held against rotation by the walls thereof. A 110 coil spring 34 is mounted around the bolt 31 between the head 30 of the bar and nut

33 so that by threading the bolt 31 through the nut 33 the spring 34 will be compressed.

A locking ring 35 is fitted over the head of the bolt 31 and is provided with lugs 5 36 which engage the bar 27 to prevent rotation of the bolt 31 and ring.

The casting 10^a extends upwardly along the sidewall of the box 7 next to the switch body and is apertured at 38 to permit the 10 rod 17^a to enter the passage 9 formed by the apertures in the box 7 and the switch body 2. The face of the casting above the aperture 38 is rounded to form a fulcrum bearing 39 for the rod 17^a.

15 In operation, when the parts are assembled, the bolt 31 will be threaded downwardly through the nut 33 thus compressing the spring 34 and forcing the rod 17^a against the fulcrum bearing 39 and causing 20 the forward end of the rod to apply a downward force against the lug 5 of the tongue 4. Due to the spring 34 between the nut 33 and rod 17^a the force applied to the rod will be yieldable and, therefore, considerable force may be applied to the rod 25 17^a and tongue without bending the rod or binding the switch tongue.

When it is desired to remove the rod 17^a for repairs or renewal, the pin 28 is removed, the locking ring 35 is removed, and the bolt 31 is then unthreaded from the nut 33 so as to permit removal of the bolt and spring 34. The bar portion 27 is then telescoped within the tubular portion 26, and 35 the telescoped rod 17^a is then moved rearwardly within the box 7 and tilted upwardly so as to clear the box.

While I have shown and described certain specific embodiments of my invention 40 it will be understood that I do not wish to be limited thereto, since various modifications may be made without departing from the scope of my invention as defined in the appended claims.

45 I claim—

1. A tongue switch comprising a switch body, a tongue mounted in a suitable groove in said body, a lug projecting downwardly intermediate the ends of said tongue, a box 50 secured to one side of said switch body, said switch body and said box being apertured to form a connecting passage, a holding rod engaged with said lug and extending into said box, and means for holding said rod against upward movement.

2. A tongue switch comprising a switch body, a tongue mounted in a suitable groove in said body, a lug projecting downwardly intermediate the ends of said tongue, a box 60 secured to one side of said switch body, said switch body and said box being apertured to form a connecting passage, a holding rod engaged with said lug and extending into said box, and means in said box for preventing upward movement of said rod.

3. A tongue switch comprising a switch body, a tongue mounted in a suitable groove in said body, a lug projecting downwardly intermediate the ends of said tongue and apertured in a direction transversely of the 70 longitudinal axis of said tongue, a box secured to one side of said switch body, said switch body and said box being apertured to form a connecting passage, a holding rod mounted in said box and extending through 75 said passage and said apertured lug on said tongue, said rod being normally held against movement in an upward direction and in a direction transversely of the longitudinal axis of said tongue, and said lug on said tongue being adapted to move on said rod when said tongue is moved from side to side of said body.

4. A tongue switch comprising a switch body, a tongue mounted in a suitable groove 85 in said body, a lug projecting downwardly intermediate the ends of said tongue and apertured in a direction transversely of the longitudinal axis of said tongue, a box secured to one side of said switch body, said switch body and said box being apertured to form a connecting passage, a holding rod mounted in said box and extending through 90 said passage and said apertured lug on said tongue, said rod being normally held against movement in an upward direction and in a direction transversely of the longitudinal axis of said tongue, whereby said tongue is held down on said body by said rod, means 95 for stiffening said rod, and said lug on said tongue being adapted to move on said rod when said tongue is swung from side to side of said body.

5. A tongue switch comprising a switch body, a tongue mounted in a suitable groove 105 in said body, a lug projecting downwardly intermediate the ends of said tongue and apertured in a direction transversely of the longitudinal axis of said tongue, a box secured to one side of said switch body, said switch body and said box being apertured to form a connecting passage, a holding rod having one end removably secured in said box and having its other end extending 110 through said passage and said apertured lug, and means for forcing said rod downwardly against said lug to prevent upward movement of said tongue, said lug on said tongue being adapted to move on said rod when said tongue is swung from side to side 115 of said body.

6. A tongue switch comprising a switch body, a tongue mounted in a suitable groove in said body, a lug projecting downwardly 125 intermediate the ends of said tongue and apertured in a direction transversely of the longitudinal axis of said tongue, a box secured to one side of said switch body, said switch body and said box being apertured to form a connecting passage, a holding rod 130

having one end removably secured in said box and having its other end extended through said passage and said apertured lug, means for holding said rod against movement in a direction transversely of the longitudinal axis of said tongue, and means for forcing said rod downwardly against said lug to prevent upward movement of said tongue, said lug on said tongue being adapted to move on said rod when said tongue is swung from side to side of said body.

7. A tongue switch comprising a switch body, a tongue mounted in a suitable groove in said body, a lug projecting downwardly intermediate the ends of said tongue and apertured in a direction transversely of the longitudinal axis of said tongue, a box se-

cured to one side of said switch body, said switch body and said box being apertured to form a connecting passage, a crank lever pivotally mounted in said box, one arm of said lever being slotted and the other arm of said lever being apertured, a holding down rod having one end slidably mounted in said lug, and having its other end passed through said slotted crank arm and engaged in the aperture in the other crank arm of said crank lever, and means for moving said crank lever about its pivotal mounting so as to cause said slotted arm to force said rod downwardly thereby holding said tongue against upward displacement.

In testimony whereof, I have hereunto set my hand.

CHARLES W. COLLINS.
